Inventor
Harry Howell,

By *Clarence O'Brien*
Attorney

UNITED STATES PATENT OFFICE

HARRY HOWELL, OF CLEVELAND, OHIO

COPPER COIL WATER HEATER CONSTRUCTION

Application filed November 11, 1930. Serial No. 494,978.

This invention relates broadly to water heaters, and has more particular reference to that type of water heater including a double copper coil through which the water to be heated is conducted.

A primary object of the present invention is to provide suitable means whereby, by taking advantage of the resiliency in the coil, to either lengthen or shorten the distance between the top and bottom connections of the coil as may be required, the coil may be shortened or lengthened, for coupling with the conduit pipes leading to and from the boiler without the necessity of removing the coil and at the same time compensate for the expansion and contraction as occasioned from the hot and cold water circulating through the coils, and the conduit pipes associated therewith.

Other objects and advantages of the invention will become apparent during a study of the following description taken in connection with the accompanying drawings, wherein:

Figure 1 is an elevational view of a heater embodying the features of my invention.

Fig. 2 is a longitudinal sectional view therethrough, taken at substantially right angles to Fig. 1.

Fig. 3 is a top plan view from the heater casing, the heater coils being removed.

With reference more in detail to the drawings, it will be seen that I have shown a conventional type of water heater including the usual jacket or casing 5, having the double copper water circulating coils 6 mounted therein, and suitably arranged in the bottom of the jacket or casing 5 is the conventional valve controlled burner 7.

As comprehended by the present invention, the uppermost convolutes of the inner and outer coils of the double heating coil terminate in an upwardly directed manifold or coil coupling 8 communicating with the inner and outer coils. The manifold 8 extends upwardly through a notch 14 in the top wall of the casing, and at its upper extended end is threaded for threaded engagement with the lower end of a pipe (not shown), which leads to the top of the water boiler (not shown).

The lowermost convolutes of the inner and outer coils, and as well known in the art, are in communication with a manifold 9, which intake manifold 9 extends through an opening 10 in the wall of the casing, and at its outer extending intake end, the manifold 9 is threaded as at 11 for threaded engagement with the water feed pipe (not shown).

As further comprehended by the invention, the opening 10 through which the intake of the manifold 9 extends, is of greater diameter than said intake, to permit freedom of movement vertically through the opening 10. For normally closing the slot or opening 10, there is provided a rectangular plate 12, provided intermediate its upper and lower ends with a suitable opening for accommodating the extended threaded end of the manifold 9.

A nut 13 is threaded on the end of the manifold 9 and bears against the plate 12 for normally retaining the plate in position on said manifold.

The casing 5 at the upper end thereof and in longitudinal alignment with the opening 10 is provided with a vertically disposed notch 14 communicating at its upper end with the notch 14'. The outlet manifold 8 adjacent its lower end is provided with a laterally extended threaded extension 15 extending through the notch 14 and adapted for vertical movement within the notch.

Carried on the extension 15 and disposed against the outer face of the casing 5 is an elongated plate 16 provided with an opening intermediate its upper and lower ends for accommodating the extension 15. A retaining nut 17 is threaded on the extension 15 and bears against the plate 16 for retaining the same in contact with the casing 5.

From the foregoing, it will be seen that I have provided means for utilizing the expandable and contractible qualities of the coil to permit adjustment in the length of the coil without the necessity of removing the coil and whereby the coil may be either lengthened or shortened the required distance between the top and bottom connections of the coil with the conventional pipe fittings, leading to the intake manifold 9 and the conven-

tional water pipe, leading from the outlet manifold 8.

Furthermore, it is to be understood that the plate 16 is to be retained loosely against the casing to slide freely parallel to the casing whereby, through the natural springiness of the multiple circulating coil the same may be lengthened or shortened as required when coupling the pipe or outlet 8 to the pipe leading to the boiler.

Thus, as before stated, my improvement permits, because of the flexibility of the coil, the lengthening of the coils, or the shortening thereof as may be necessary in making the connections to the boiler, this being the case in event the riser pipe to the boiler should be cut a trifle too long or too short.

Even though I have herein shown and described the preferred embodiment of my invention, it is to be understood that the same is susceptible to changes fully comprehended by the spirit of the invention as herein described and the scope of the appended claims.

Having thus described my invention, what I claim as new is:—

1. In combination, a water heater comprising a casing, said casing having top and vertical side walls, a notch extending transversely of the top wall of the casing and vertically along the vertical wall of the casing at the top thereof, a resilient water circulating coil arranged within said casing, an outlet manifold at the top of the coil extending through the notch in the top of the casing, an extension provided on the manifold and extending through the notch in the vertical wall of the casing, said casing adjacent its lower end being provided with a relatively large opening, an intake manifold for the coil at the lower end of the coil, and having an end portion thereof extending through said opening, a plate on the extension of the intake manifold, a nut threaded on said extension of the intake manifold for securing said plate thereon and adjacent the wall of the casing, and said first-mentioned extension having a plate arranged thereon for slidable contact with the wall of the casing, and a nut threaded on the first-mentioned extension for retaining the plate in position thereon.

2. In combination, a water heater including a casing, a multiple water circulating coil arranged within the casing and provided with an inlet manifold and an outlet manifold, and means for mounting said coil within the casing, said means including a projection provided on said inlet manifold and projecting through a slot provided in the wall of the casing, means engageable with said projection for normally retaining the same against casual movement relative to the slot, a projection provided on the outlet manifold and extending through a second slot provided in the wall of said casing, and means engageable with the second mentioned projection

and slidably contacting the wall of said casing, whereby said second projection may be moved longitudinally of its slot for expanding or contracting the circulating coil to facilitate coupling of the outlet manifold to a conduit pipe of a boiler.

In testimony whereof I affix my signature.

HARRY HOWELL.
